UNITED STATES PATENT OFFICE

2,255,485

TELEVISION RECEIVER

Robert B. Dome, Bridgeport, Conn., assignor to
General Electric Company, a corporation of
New York

Application December 15, 1939, Serial No. 309,443

11 Claims. (Cl. 178—7.5)

My invention relates to television receivers and more particularly to means for controlling the background brilliance of the reproduced picture.

It has for one of its objects to provide improved means to control the background brilliance of the reproduced picture in accordance with the background brilliance of the transmitted picture as represented by the intensity of the picture signal currents as received in the receiver.

In my copending application Serial No. 243,134 filed November 30, 1938 and entitled Automatic background control for television systems, I have illustrated a system in which the background brilliance of the reproduced picture is controlled in accordance with a unidirectional electromotive force produced by rectification of the television picture signal, this rectification occurring in the grid circuit of an amplifier of the television signals. That system possesses the advantage that the cathode of the picture reproducing device is maintained substantially at the potential of the cathode of the picture signal amplifier whereby the heaters for these cathodes may be energized from the same source and a minimum of insulation between the cathode and heater of the picture reproducing device is therefore required.

My present invention has for another of its objects substantially to retain this advantage, and at the same time to secure improved operation and reduced cost of the system.

A particular object of my invention is so to arrange the circuits as to reduce the cost of the equipment necessary to supply the high voltage operating potential for the picture reproducing discharge device.

Still another object of the invention is to provide improved means to prevent damage to the cathode ray screen during the heating up period of the cathodes of the system before the deflection potentials are applied to the deflection system of the picture reproducing device.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Fig. 1 represents an embodiment of my invention, and Figs. 2 and 3 represent modifications thereof.

Referring more particularly to Fig. 1 of the drawing, my invention is illustrated as embodied in a television receiver, only a portion of which

is shown, but which receives the television modulated carrier wave, demodulates it, and supplies the reproduced television picture signal electromotive force between terminals 10 and 11 shown on the drawing. This electromotive force, representing the transmitted picture is supplied through a coupling condenser 12 to a control electrode 13 provided in an electron discharge amplifier 14.

This electromotive force has alternating current intensity variations therein which are in accordance with the gradations of shade of an element of area of the picture transmitted as said element is scanned over the picture. These variations I shall refer to as the picture signal. It also has a certain average, or overall, intensity which is dependent upon the overall, or background, brilliance of the picture.

The grid circuit of the device 14 is provided with the grid condenser 12 and a grid leak 12'. This leak 12' is connected, for direct current, across the condenser 12 through apparatus, not shown, which is connected to terminals 10 and 11, so as to provide a discharge path for the condenser. This grid leak and condenser combination 12, 12' has such a time constant that upon occurrence of rectification in the grid circuit of the discharge device 14 a unidirectional potential is produced upon resistance 12' having a magnitude, which is dependent upon the background, or overall, brilliance of the transmitted picture. This electromotive force is utilized in the manner presently to be described to control the brilliance of the reproduced picture.

35 The discharge device 14 has a cathode 15, an anode 16 and a suppressor grid 17, all connected in a conventional manner to amplify the picture signals supplied to the grid 13 thereof. The anode 16 is supplied with operating potential 40 from the power supply rectifier 18 of the television receiver through a resistor 19. The device 14, likewise, has a screen grid 20 which is supplied with operating potential from the rectifier 18 through a resistor 21. The rectifier 18 also supplies operating potential for other discharge devices of the television receiver through conductor 22 and ground.

The picture signal output of the amplification stage 14 is developed upon resistance 19 and is supplied through a coupling condenser 23 to a control electrode 24 provided in a picture reproducing cathode ray device 25 thereby to control the intensity of the cathode ray in that device. The picture reproducing device 25 has a cathode 26, which is connected to the movable contact 27

of a potentiometer 28, connected across the output of the power supply rectifier 18.

The biasing circuit for the control electrode 24 of the picture reproducing 25 is completed through a resistor 31 to the junction between a pair of resistors 32 and 33, which are connected in series between the left-hand terminal of the resistor 21 and the negative terminal of the potential source 18. The upper terminal of the resistor 32, and hence the screen grid of device 14, is maintained at ground potential for currents of signal frequency by condenser 34, which is connected between the upper terminal of the resistor 32 and ground. In similar manner, a by-pass condenser 35 maintains the cathode 26 at ground potential for alternating currents.

The picture tube 25 is provided with a first, or acceleration, anode 36 and a second anode 37, the latter being connected to the positive terminal of a source 38 of relatively greater potential than that of source 18, and which may comprise a second power supply rectifier connected across a resistance 39 as indicated by the + and - signs on the drawing. The negative terminal of this source 38 is connected to the positive terminal 25 of the potential source 18 and to the acceleration anode 36, the potentials of the source 18 and 38 thus being applied in aiding relation between the cathode 26 and the anode 37 of the picture reproducing device 25.

The heaters 43 and 44 for the cathodes of the various discharge devices are shown connected to the same energization circuit 43. The heaters of the cathodes of other discharge devices in the receiver may also be heated from this same circuit through conductors 41. This may include the discharge devices which generate the scanning, or deflection, potentials for the cathode ray device. Any of the heaters may, of course, be supplied through individual circuits from 40 separate secondary windings on a common transformer such as that which supplies potential to rectifier 18, if desired.

The discharge devices of the receiver, which generate the scanning potentials for device 25, 45 since they usually have indirectly heated cathodes, are inoperative to produce the scanning, or deflection, potentials until their cathodes have had time to become properly heated after the receiver is initially energized. This condition 50 necessitates the use of means, which will be presently described, to protect the screen of the cathode ray device from injury due to impingement of the beam thereon during this initial heating period after the receiver energizing circuits have 55 been energized.

The picture reproducing device 25 is also provided either with deflection electrodes, or deflection coils, not shown, which are energized from the scanning circuits of the television receiver. 60 Such systems are entirely conventional and operate in the usual way to deflect the cathode ray of the picture reproducing device 25 across the screen of that device in such a fashion that when modulated by the control electrode 24, it reproduces the transmitted picture upon the cathode ray screen.

The picture reproducing device is also provided with a focusing coil 46 the function of which, when energized, is to focus the cathode 70 ray upon a small area, or spot, on the screen. This coil is connected, however, in the negative return lead of rectifier 18; that is, between ground at 41 and the anodes of the electron discharge rectifier 42, so that it is not energized upon initial 75

energization of the cathode of rectifier 42, which commonly is of filamentary type, as when power is first applied to the television receiver, and becomes energized only after the cathode of the various discharge devices energized thereby have had time to heat up so that current flows from the rectifier. This means that in the event that the cathode of the picture reproducing device 25 becomes effective to emit the cathode ray prior to application of scanning potentials to the deflection system of this device the ray is not focused upon the screen, but falls upon such a large area thereof that it is insufficiently intense at any point to produce injury to the screen. After the cathodes of the discharge devices of the receiver become heated, and current flows from the rectifier, focusing coil 46 becomes energized and the ray is focused upon the screen. By this time the cathodes of the other discharge devices of the receiver are also heated with the result that the deflection potentials are generated and applied to the cathode ray device, thereby to deflect the ray over the screen for normal operation.

In explaining further the operation of the device described, it will first be assumed that no picture signals are present at the input terminals 10, 11, a condition which represents the transmission of a totally black picture. The grid 13 of the discharge device 14 has zero bias and the device draws maximum anode and screen grid current. The screen grid current, in flowing through the resistor 21, produces a voltage drop across this resistor thereby to establish a predetermined voltage drop across the resistors 32 and 33, which are connected in the biasing circuit of the control electrode 24 of the picture reproducing device 25. The control electrode 24 is biased by the difference in the potentials appearing across resistor 33 and that appearing across the lower portion of potentiometer 28 below the movable contact 27, these potentials being in opposed relation. Under the condition that no picture signals are present at the input terminals 10, 11, the movable contact 28 is adjusted along the potentiometer 27 to a point where the control electrode 24 of the picture reproducing device 25 is just biased to cutoff. The fluorescent screen of the picture reproducing device is then dark as is proper for a black picture.

Now assume that a picture signal is supplied to the input terminals 10, 11 corresponding to a picture composed of light and dark areas. The control electrode 13 of the device 14 becomes positive during a portion of each alternating current cycle of the picture signal and rectification of the signal between the control electrode 13 and the cathode 15 ensues thereby charging condenser 12, as in ordinary grid leak and condenser rectification, until the control electrode is biased negatively in proportion to the maximum change in the picture signal caused by the lighter areas of the television picture. This change in the bias of the control electrode 13 is thus dependent upon an integrated change in the picture signal produced by gradations of light intensities between the light and dark areas of the picture and thus it corresponds with the overall brilliance of the televised picture.

As the control electrode 13 is biased more negatively by rectification of the picture signal, the anode and screen grid currents are thereby decreased. A decrease in the screen grid current produces a corresponding decrease in the potential drop across the resistor 21 and a cor-

responding increase in the potential drop across the resistor 33 which, in turn, varies the potential of grid 24 in the positive direction. The bias on the control electrode 24 of the picture tube 25 is therefore varied in the positive direction with increasing values of the potential drop across the resistor 33. It will thus be evident that the overall brilliance of the televised picture controls the bias of the control electrode 18 of the device 14 and by controlling the screen grid current of this device, directly controls the bias of the control electrode 24 thereby automatically to control the overall brilliance of the picture reproduced on the fluorescent screen of the picture reproducing device.

It has been found advisable for best operation to choose a value for the resistors 32 and 33 such that the same change of potential drop occurs across the resistor 33 as occurs across the resistor 19 with changes in the overall brilliance of the televised picture. In this way, the amplification, or gain of device 14, for the alternating current, or picture, component of the television signal applied to the control electrode 24 is the same as the amplification, or gain of this device for the direct current or background component of the television signal. Thus these two components of the received signal as applied to the cathode ray device are maintained in their proper relationship to each other.

By proper choice of resistors 32 and 33 with respect to each other to increase, or decrease, the voltage on resistance 33 the background changes may be exaggerated, or they may be made subnormal in amount as desired, thereby to produce special effects as desired. In this way, compensation may be effected for attenuation of background signal in the system prior to discharge device 14.

It has been found in practice that with the system constructed in accordance with my invention the cathode 26 of the picture reproducing device may be operated near the potential of the cathode of device 14 and near ground. This enables the picture reproducing device to be constructed with a minimum of insulation between its heater element 44 and the cathode 26. The heater 44 may thus be heated by the same source of heating energy as is used to heat the cathode heater 40 of the discharge device 14, as shown, or if energized from separate windings of a transformer, for example, it renders possible a reduction in cost of the insulation necessarily provided to insulate such windings from each other and from ground.

An additional advantage of my invention resides in the fact that the potential sources 39 and 18 may be connected in series between the cathode 15 and the anode 37 of the picture reproducing device. With the potential sources 39 and 18 connected as shown, the bleeder resistor 38 across the anode source 39 can be dispensed with, or a much higher resistance, such as 20 megohms, employed since it is not necessary to provide a tap connection from any such bleeder to any electrode such as the anode 36 and it is not necessary that such resistance carry any great amount of current. This produces a saving in the power required from the source 39, thereby effecting a saving in the size and cost of the elements which constitute this source in addition to effecting a saving of the cost of the bleeder resistor itself. This results in a higher available voltage from a given source 39 for the anode 37.

In one embodiment of my invention the circuit elements have the following values:

Resistance 32	megohms	2.2
Resistance 33	do	1
Resistance 21	ohms	56,000
Resistance 28	do	10,000
Resistance 19	do	1,800
Resistance 31	Zero	
Capacity 34	microfarad	.25
Capacity 23	do	.25

These values are given merely by way of example and may vary widely in different installations. They are not intended as any limitation of my invention.

Fig. 2 represents a modification of my invention in which the lower terminal of resistance 28 is connected to ground through diode 45. When so connected, during the initial heating up period of diode 45, the cathode of which may be energized from circuit 43 of Fig. 1, resistance 28, and hence the cathode 26 of device 25 is at the full potential of the rectifier 18. The grid of this device is maintained near ground potential through resistance 33 and hence it is highly negative relative to its cathode. This prevents the cathode ray from impinging upon the screen until such time as the deflection potentials are applied and the cathode of diode 45 has become heated. In this way the connection of the focusing coil 46 in the negative lead of rectifier 18, as shown in Fig. 1, may be obviated.

Fig. 3 is similar to Fig. 1 but differs therefrom in that the lower terminals of resistances 28 and 33 are connected, not to ground as in Fig. 1 but to a point 50 of potential negative with respect to ground. The negative side of the rectifier 18 is, in this case, connected to ground through a resistance 51 upon which a potential develops which is negative with respect to ground. This means that the tap 27, and hence the cathode 26 of device 25, may be adjusted to be even nearer to or at the potential of the cathode of device 14.

While I have shown a particular embodiment of my invention, it will, of course, be apparent that I do not wish to be limited thereto since many modifications may be made both in the circuit arrangement and in the instrumentalities employed, and I, therefore, contemplate by the appended claims to cover all such modifications as fall within the true spirit and scope of my invention.

What I claim as new and desire to secure by Letters Patent of the United States is:

1. The combination, in a television receiver, of a cathode ray picture reproducing device having a cathode and a control electrode, an amplifier having an anode circuit, a screen grid circuit, and a control grid circuit, means to supply to said control grid circuit signal currents representing the transmitted picture and its background brilliance, means to develop in said anode circuit electromotive force representing the transmitted picture and to supply said electromotive force between said control electrode and cathode of said picture reproducing device, means to develop in said screen grid circuit by reason of current flowing between said screen grid and cathode an electromotive force representing the background brilliance of said picture, and means to supply such electromotive force between the cathode and control electrode of said cathode ray device.
2. The combination, in a television receiver,

of a cathode ray picture reproducing device having a cathode and a control electrode, an amplifier having an anode, a screen grid, a control grid, and a cathode, means to supply between said cathode and control grid of said amplifier picture signals and background signals, means to develop on said anode potentials representing said picture signals, and on said screen grid in response to current flowing between said screen grid and cathode potentials representing said background signals, means to supply a normal operating bias potential between the control electrode and cathode of said picture reproducing device, means to vary said bias potential in accordance with the potential on said screen grid, and means to supply said potentials representing said picture signals from said anode to said control electrode.

3. The combination, in a television receiver, of an amplifier including a cathode, an electron-receiving electrode and an anode, a resistance connected between said cathode and electron-receiving electrode, a source of operating potential connected through a second resistance both between said cathode and electron receiving electrode and across said first resistance, whereby the potential on said first resistance increases and decreases as current in said electron-receiving electrode and said second resistance decreases and increases, a cathode ray picture reproducing device having a cathode connected to a point on said source and a control electrode connected to an intermediate point on said first resistance, said points being such as to provide operating bias potential between said cathode and control electrode of said cathode ray device, means to transmit picture signals through said amplifier and from said anode thereof to the control electrode of said picture reproducing device thereby to reproduce the transmitted picture, and means to control the current in said electron-receiving electrode thereby to vary the potential on said first resistance and on said control electrode of said cathode ray device to control the background brilliance of said picture.

4. The combination, in a television receiver, of an amplifier having a cathode, an anode and an electron receiving screen electrode interposed therebetween, a source of operating potential for said electron-receiving electrode and anode, a resistance path across said source, an electron discharge picture reproducing device having a cathode connected to an intermediate point on said source, and a control electrode connected for low frequency and unidirectional currents to an intermediate point on said path, means to transmit signals representing said picture through said amplifier and to produce on said anode voltages of high frequency varying with said picture and on said screen electrode voltage of low frequency varying with the background brilliance of said picture whereby the bias on the control electrode of said picture reproducing device is varied in accordance with the background brilliance of said picture, and a high frequency coupling for picture signals between said anode and the control electrode of said picture reproducing device.

5. The combination, in a television receiver, of an amplifier having a cathode, a control electrode, and a pair of output electrodes, a source of operating potential connected between said cathode and each of said output electrodes through respective resistors, a by-pass for pic-

ture signal currents between said cathode and one of said output electrodes, means to supply alternating picture signals and unipotential background signals to said control electrode whereby said background signals appear upon said resistance connected to said one output electrode and the picture signals appear upon the other of said resistors, an electron discharge picture reproducing device connected to respond to said picture and background signals appearing on said resistors, and means whereby the amplification of said amplifier for said picture signals is substantially equal to that for said background signals.

15. 6. The combination, in a television receiver, of an amplifier having a cathode, a control electrode, and a pair of output electrodes, a source of operating potential connected between said cathode and each of said output electrodes, through respective resistors, a by-pass for picture signal currents between said cathode and one of said output electrodes, means to supply alternating picture signals and unipotential background signals to said control electrode whereby said background signals appear upon said resistance connected to said one output electrode and the picture signals appear upon the other of said resistors, an electron discharge picture reproducing device connected to respond to said picture and background signals appearing on said resistors.

35. 7. The combination, in a television receiver, of a picture signal amplifier having a cathode, an electron receiving electrode and a picture signal output, an electron discharge picture reproducing device having a cathode, a control electrode, an acceleration anode and a high potential anode, a source of operating potential having its positive terminal connected to said acceleration anode and to said electron receiving electrode and points at low potential thereon connected respectively to the cathode of said amplifier and the cathode of said picture reproducing device, a resistance path across said source having intermediate points thereon connected for unidirectional and low frequency currents to said electron receiving electrode and to said control electrode respectively, means to vary the current in said electron receiving electrode in accordance with background signals, said resistance path being so proportioned that the potential on said control electrode varies sufficiently in response to changes in current in said electron receiving electrode to control the background brilliance of the reproduced picture, a coupling for picture signals between said picture signal output and said control electrode, and a source of operating potential connected between said acceleration anode and high potential electrode whereby said cathodes are maintained near the same potential, said sources are utilized in series, and both picture signals and background signals are derived from said amplifier.

60. 8. The combination, in a television receiver, of a picture signal amplifier having a cathode, an anode, and a screen electrode, an electron discharge picture reproducing device having a cathode, a control electrode, an acceleration electrode and a high potential anode, a source of operating potential having its positive terminal connected to said acceleration electrode, to said anode of said amplifier and through a resistance to said screen electrode, and having

points at low potential connected to said cathodes, a coupling for picture signals between said anode of said amplifier and said control electrode of said picture reproducing device, means to vary the current in said screen electrode and in said resistance in accordance with background signals thereby varying the voltage on said screen electrode, and means to supply a portion of the unidirectional voltage variation existing between said screen electrode and cathode of said amplifier between said control electrode and cathode of said picture reproducing device thereby to control the background brilliance of the reproduced picture, whereby both picture signals and background signals are supplied from said amplifier and both of said cathodes are at low potential.

9. The combination, in a television receiver, of an amplifier having an anode, a cathode, a control electrode, and a screen electrode, an electron discharge picture reproducing device having a cathode, a control electrode, an acceleration anode, and a high potential electrode, a source of operating potential connected between the anode and cathode of said amplifier, the positive terminal of said source being connected to said acceleration anode and an intermediate point thereof being connected to the cathode of said picture reproducing device, a resistance path across said source, said screen grid and said control electrode of said picture reproducing device being connected to intermediate points on said path whereby the potential on said control electrode varies responsively to current variations in said screen electrode, an additional source of operating potential connected between said acceleration anode and high potential electrode, a coupling for picture signals between the anode of said amplifier and the control electrode of said picture reproducing device, and means to supply alternating picture signals and unidirectional background signals to the control electrode of said amplifier.

10. The combination, in a television receiver, of an amplifier having a cathode and an electron receiving electrode, a picture reproducing device having a cathode, a control electrode, and an anode, a source of potential connected between said cathode of said amplifier and anode of said picture reproducing device, two shunts across said source, said electron-receiving electrode and control electrode being connected to

- intermediate points on one of said shunts and said cathode of said reproducing device being connected to intermediate low potential points on the other of said shunts, said shunts being so proportioned and said points so positioned thereon that bias potential controlled by the current in said receiving electrode is supplied between the control electrode and cathode of said picture reproducing device from said shunts, and means effective upon energization of said receiver to maintain the connection of said other shunt to the negative terminal of said source interrupted for a predetermined period, whereby the cathode of said reproducing device is positive with respect to said control electrode during said period, and thereafter to complete said connection whereby the cathode of said reproducing device attains a value near the potential of the cathode of said amplifier.
11. The combination, in a television receiver, of an amplifier having a cathode and an electron receiving electrode, a picture reproducing device having a cathode, a control electrode, and an anode, a source of potential connected between said cathode of said amplifier and said anode of said picture reproducing device, two shunts across said source, said electron-receiving electrode and control electrode being connected to intermediate points on one of said shunts and said cathode of said reproducing device being connected to low potential point on the other of said shunts, said shunts being so proportioned and said points so positioned thereon that bias potential controlled by current in said receiving electrode is supplied between the control electrode and cathode of said picture reproducing device from said shunts, said other shunt including a diode connected therein between the negative terminal of said source and said cathode of said reproducing device, said diode having a heater, and a cathode heated thereby, and means to energize said heater upon energization of said receiver, said heater requiring a predetermined time to heat said cathode sufficiently to render said diode conductive, whereupon the potential of said cathode of said reproducing device is reduced from a value positive with respect to the potential of said control electrode to a value near the potential of the cathode of said amplifier.

ROBERT B. DOME.
